UNITED STATES PATENT OFFICE.

WILLIAM B. CHAPLIN, OF WEST NEWBURY, MASSACHUSETTS.

DESIGN FOR A LAST.

SPECIFICATION forming part of Design No. 26,161, dated October 6, 1896.

Application filed February 11, 1896. Serial No. 578,958. Term of patent 14 years.

To all whom it may concern:

Be it known that I, WILLIAM B. CHAPLIN, a citizen of the United States, residing at West Newbury, in the county of Essex and State of Massachusetts, have invented a certain new and useful Design for Lasts, of which the following is a specification, reference being had therein to the accompanying drawings.

- 10 My invention is a last used in the manufacture of boots and shoes, as is well known in that art, and presents certain details of form, which I will now describe in detail in connection with the accompanying drawings, 15 in which—
Figure 1 is a perspective view of the last. Fig. 2 is a cross-section thereof upon the line 2—2, and Fig. 3 is a view of the bottom of the last.
20 In all of the views the same numeral indicates or represents the same part.

1 is the last proper, and is turned in the usual manner from pear or box wood. Around the edge 2 of the sole portion 3 of the last there is rabbeted an open groove 4, this rabbet 4 being the leading and essential feature of my design, and for purposes neither essential nor proper of description in this application. 25

What I claim, and desire to secure by my 30 Letters Patent, is—

The design for a last, substantially as herein shown and described.

In testimony whereof I affix my signature in presence of two witnesses.

WILLIAM B. CHAPLIN.

Witnesses:

JOSEPH H. PEARL,
CHARLES S. GOODWIN.
